GRATE CLIP FOR TRAVELING GRATE
STOKERS

Fred B. Hall, Worcester, Mass., assignor to Riley
Stoker Corporation, Worcester, Mass., a cor-
poration of Massachusetts

Application January 30, 1948, Serial No. 5,424

4 Claims. (Cl. 110—40)

1

This invention relates to grate clips for traveling grate stokers, and more particularly to grate clips of the general type shown in the patent to Krieger No. 1,917,652, granted July 11, 1933, such clips having depressed portions at their trailing ends and elevated fuel supporting portions at their leading ends which overlie the depressed portions of the adjacent clips.

It is one object of the invention to provide a grate clip which will ensure a more efficient distribution of the air for combustion.

It is a further object of the invention to provide a grate clip which will to a considerable extent avoid the sifting of fine particles of fuel or ash into the air compartments of the stoker.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a perspective view of a grate clip;

Fig. 2 is a longitudinal section through a portion of a traveling grate, showing the grate clips in side elevation;

Fig. 3 is a view similar to Fig. 2 but on a smaller scale, and further showing the general arrangement of the rear portion of the stoker; and

Fig. 4 is an enlarged section taken on the line 4—4 of Fig. 2.

Referring first to Figs. 2 and 3, there is shown a transverse horizontal rear girder 10 supported at each end on a vertical pedestal 11. Two or more members 12 (one only being shown) are mounted on the rear face of the girder to provide curved tracks for endless parallel grate chains which pass around the girder. These chains are formed of links 14 pivotally connected to each other by means of pins 15. The pins carry rollers 16 which roll upon the track 12 as the chain moves thereover, and a shoe 18 is provided to guide the chain onto the lower track (not shown), all of which is well known in this art. The space 19 in front of the girder is enclosed by a compartment bottom plate 20 and an air seal 21, and air is supplied to this space under pressure from any suitable source.

A series of spaced parallel grate supporting bars are arranged transversely of the stoker, and as illustrated these comprise angles 23 fastened to the links 14 by bolts 24, and T-shaped members 25 riveted to the angles. These transverse bars carry the grate clips 27 which form the actual fuel supporting surface.

2

As best shown in Figs. 1 and 4, each grate clip 27 is in the form of an elongated narrow metal body comprising a vertical web 28 and a flange 29 extending horizontally from one side of the web at the upper edge thereof. The leading portion 31 of the clip is elevated to provide the fuel support proper, whereas the trailing portion 32 is depressed and at assembly extends beneath the portion 31 of the corresponding clip in the next row. The fuel supporting portion of the flange 29 is preferably somewhat thicker than the remainder of the flange, and on its edge there are provided a series of spaced Z-shaped ribs 33 forming tortuous channels 34 therebetween for the flow of air upwardly to the fuel bed. Spaced transverse grooves 36 are provided in the top of the fuel supporting portion 31 to aid in distributing the air laterally. A boss or enlargement 37 is provided on the web 28, intermediate the ends of the clip, and this boss is formed with a T-shaped slot or opening 38 therethrough which fits the adjacent member 25 somewhat loosely. This boss 37 is offset from the center of gravity of the clip in a direction toward the trailing portion 32, so that the leading end of the clip will rest by gravity on the trailing portion of the adjacent clip.

Each grate clip 27 is provided with means for ensuring a substantially uniform distribution of air among the channels 34 and for avoiding the deposit of fuel or ash particles in the air chamber 19. For this purpose a flange 40 extends horizontally from the web 28 beneath and spaced downwardly from the fuel supporting portion of the flange 29 and forwardly to the leading end of the clip. A portion of this flange 40 forms the upper wall of the slot 38. Three small shallow notches 42, 43 and 44 are provided in the edge of the flange 40 in order that air may flow upwardly therethrough from the chamber 19. In addition a large deep notch 46 is provided in this flange near the leading end of the clip in order that fine particles of fuel or ash which have been deposited on the flange may be discharged therethrough as the clip tips downwardly at the rear of the stoker. Preferably the notch 46 extends all the way to the web 28. A small shallow notch 48 is provided in the edge of the flange 29 on the trailing portion of the clip in position to register with the large notch 46 of the adjacent clip. Thus the flange 29 on the trailing portion of one clip will substantially close the notch 46 thereabove, permitting only such air flow as may take place through the notch 48.

It will now be apparent that in the operation 55 of the invention, the air flowing upwardly from

the chamber 19 must pass through the small notches or openings 42, 43, 44 and 48 in order to reach the air channels 34 which direct it into the fuel bed carried by the clips. Consequently these notches provide metering restrictions which will prevent excessive flow even though portions of the fuel bed may be relatively thin. In this way, the air distribution among the various grate clips is made more uniform. Furthermore the air distribution among the various air channels 34 in a given clip is rendered more uniform by the elimination of the blasting effect encountered with certain prior clips. Fine particles of ash and fuel which may sift through the air channels 34 will for the most part collect on the lower flange 40 rather than fall into the air chamber 19. As the clips tip downwardly at the end of the stoker (see Fig. 3), adjacent rows of clips will separate, and these particles of siftings will be discharged by gravity through the large openings 46. The improved clip thus provides for more efficient combustion, and eliminates the necessity for cleaning out the stoker air chambers at frequent intervals.

Having thus described my invention, what I claim as new and desire to secure by Letters Patent is:

1. A grate clip for traveling grate stokers in the form of an elongated narrow metal body comprising a vertical web, a flange at the upper edge of the web providing an elevated fuel supporting surface at the leading end of the clip and a depressed surface at the trailing end of the clip in position to underlie the leading end of an adjacent clip at assembly, the fuel supporting portion of the flange having channels therein for the flow of air to the fuel, and a lower flange located beneath the fuel supporting portion of the first mentioned flange and spaced downwardly therefrom, the said lower flange extending near the leading end of the clip and having openings therethrough for the flow of air upwardly to the said channels.

2. A grate clip as set forth in claim 1, in which the openings through the lower flange are in the form of small notches in the edge thereof.

3. A grate clip as set forth in claim 1, in which

a relatively large opening is provided in the lower flange near the leading end of the clip for the discharge of fine fuel or ash particles from the upper surface of the lower flange as the clip tips downwardly at the end of the stoker, this large opening being adapted to be located directly above the trailing depressed portion of an adjacent similar clip when the clips are in their normal fuel-burning positions.

4. A grate clip for traveling grate stokers in the form of an elongated narrow metal body comprising a vertical web, a flange at the upper edge of the web providing an elevated fuel supporting surface at the leading end of the clip and a depressed surface at the trailing end of the clip in position to underlie the leading end of an adjacent clip at assembly, the fuel supporting portion of the flange having a series of channels in its edge for the flow of air to the fuel, and a lower flange projecting from the web beneath the fuel supporting portion of the first mentioned flange and extending near the leading end of the clip, the lower flange having small notches in its edge for the flow of air upwardly to the said channels and a relatively large notch near the leading end of the clip for the discharge of fine fuel and ash from the upper surface of the lower flange as the clip tips downwardly at the end of the stoker, this large notch being adapted to be located directly above the trailing depressed portion of an adjacent similar clip when the clips are in their normal fuel-burning positions, the depressed portion of the first mentioned flange having a small notch in its edge adapted to register with the large notch of an adjacent similar clip.
